UNITED STATES PATENT OFFICE

2,459,421

TOOL POST FOR LATHES

Isham H. Fann, Washington, D. C.

Application September 20, 1946, Serial No. 698,207

1 Claim. (Cl. 82—37)

1

My invention relates to improvements in tool posts for use on lathes, the primary object in view being to provide a simply constructed tool post of few parts and inexpensive construction adapted to be locked easily and quickly against turning or twisting relative to the tool carriage of a lathe and providing for easy, quick radial and vertical adjustment of a tool holder therein.

Other and subordinate objects also comprehended by my invention, together with the precise nature of my improvements, and the advantages thereof, will be readily understood when the succeeding description and claim are read with reference to the drawings accompanying and forming part of this specification.

In said drawings:

Figure 1 is a view in side elevation of my improved tool post in a preferred embodiment thereof.

Figure 2 is a view in plan.

Figure 3 is a view in vertical section taken on the line 3—3 of Figure 2, with the tool post in a tool carriage.

Figure 4 is a similar view in transverse section taken on the line 4—4 of Figure 2, and without said carriage.

Figure 5 is a view in edge elevation of the sleeve,

Figure 6 is a view in side elevation of the stud,

Figure 7 is a view in transverse section taken on the line 7—7 of Figure 6.

Referring to the drawings by numerals, my tool post, as shown, comprises an inner upright stud 1 of cylindrical form provided with a concentric, circular, enlarged base end 2 fitted in a circular aperture 3 in a rectangular washer 4 having an undercut internal wall forming an upper edge internal flange 5 thereon overlying the base end 2. The washer 4 is designed to slidably fit in the usual T-slot 6 of a lathe tool carriage 7. The stud 1 is provided with a diametrical, vertical slot 8 therein extending from the base end 2 to within a short distance of the upper end of said stud, and also with an axial threaded socket 9 in its upper end.

A sleeve 10, of substantially oval form in cross section to reduce weight, is fitted downwardly over the stud 1, slidably, the side edges being in a common vertical plane with the slot 8. The upper end of the sleeve 10 is formed with an axial, top, reinforcing boss 11 and an axial, threaded bore 12 therein aligning with the socket 9. A binder screw 13 is threaded through the bore 12 into the socket 9 with a jam nut 14 thereon for turning against said boss 11. A pair of vertical,

2

side slots 15 are provided in the opposite side edges of the sleeve 10 and which are of the same width as the slot 8 and adapted to register therewith. These slots 15 and 8 are of the proper width to accommodate therein, with a sliding fit, the usual tool holder bar 16 which is extended through said slots with the usual cutting tool, or bit, 17 clamped in its leading end by a set screw 18. The slots 15 have bottoms 19 formed in the arcs of the curvature of the lower edge of the usual rocker bar 20 which is extended through the bottoms of said slots 15 and through the slot 8 to support the tool holder bar 16. A pair of set screws 21 with "Allen" type sockets 22 in the upper ends thereof extend downwardly in said sleeve 10 and into the slots 15 for turning against the upper edge of the tool holder bar 16.

By turning the binder screw 13 downwardly, the sleeve 10 may be clamped to the top of the tool carriage 7 to bind the washer 4 against the upper side of the T-slot 6 and thereby lock the described post to said tool carriage 7 against turning or twisting. By turning the set screws 21 downwardly, the tool holder bar 16 may be clamped between the same and the rocker bar 20. The rocker bar 20 is utilized, in the usual well known manner, to adjust the tool holder bar 16 vertically into different angular positions. The set screws 21 may be used to adjust the tool holder bar radially, as will be obvious. By loosening one set screw 21, only, the tool holder bar 16 may be removed and replaced. Radial adjustment of said tool holder bar 16 may be accomplished without disturbing the vertical adjustment as established by the rocker bar 20, and vertical adjustment without disturbing the radial adjustment.

The foregoing will, it is believed, suffice to impart a clear understanding of my invention both as regards structure, operation and advantages, and without further explanation.

Manifestly, the invention, as described, is susceptible of modification as regards structural details and combinations of parts, without departing from the inventive concept, and right is herein reserved to such modifications as fall within the scope of the appended claim.

What I claim is:

1. A tool post for use in a lathe carriage having a T-slot therein comprising a rectangular washer adapted to slidably fit in said slot and provided with an internal undercut wall, a longitudinally slotted stud extending out of said washer and adapted to project upwardly of said carriage, said stud having a base flange fitting in said

washer and locked therein by said wall of the washer, a sleeve fitting over said stud and provided with opposed side slots registering with the slot in said stud, a tool holder bar slidably extended through said slots, means to clamp said bar in the side slots of said sleeve, and means to feed said sleeve along said stud toward said washer adapting said sleeve to clampingly engage said carriage and said washer to similarly engage the top of said T-slot, the first-mentioned means comprising a rocker bar extending through said slots below said tool holder bar, and set screws in said sleeve extending into said side slots and bearing against the top of the tool holder bar.

ISHAM H. FANN.
